ECCENTRIC AND FOLLOWER MECHANISM

James L. Edelen, Kirkwood, Mo., assignor to Carter Carburetor Corporation, St. Louis, Mo., a corporation of Delaware

Application July 12, 1951, Serial No. 236,408

7 Claims. (Cl. 74—567)

1

This invention relates to eccentric and follower mechanisms, and particularly to means for reducing wear and increasing the life of such devices.

Conventional fuel pumps and vacuum booster pumps in use on internal combustion engines are frequently actuated by a lever resiliently urged into contact at one end with an eccentric mounted on the engine cam shaft. In the conventional construction a flat surface of the lever makes a line contact with the face of the eccentric. Since the entire load is applied to an extremely small bearing area, wear on the bearing surfaces is very severe, particularly on the lever, which eventually may wear completely through. Wear, however, is not confined to the lever contact face, but also is very severe on the eccentric surface, substantially reducing the diameter thereof, as well as causing the cutting of grooves therein due to irregularity in the wearing down of the lever.

It is, therefore, the object of this invention to provide means for increasing the service life of eccentric operating mechanisms for pumps by eliminating the excessive wear inherent in the bearing surfaces of present types of eccentric and follower mechanisms.

A further object is to provide means whereby the permissible load on eccentric and follower mechanisms of this type may be substantially increased.

A further object is to provide a slow-wearing cam follower device which may be readily substituted for the present conventional followers in pump operating mechanisms, without any alteration to the eccentric or pump construction.

I achieve the above objects by providing the pump operating lever with a slidably or pivotally mounted contact shoe having a concave arcuate contact face, the arc of the contact face being the same radius as the eccentric. The mating arcuate faces of the shoe and eccentric thus provide a large bearing area as compared with the line contact of the conventional structure, thereby distributing the load over the entire area without concentration on any restricted portion thereof as in the present construction. With the slidably mounted shoe an equally large bearing surface may likewise be provided between the flat undersurface of the shoe and the surface of the lever, thus permitting similar load distributions and similarly inhibiting wear.

Other objects and advantages will appear from the specifications when read with the accompanying drawing, in which:

Fig. 1 shows one form of slidably mounted con-

2

tact shoe and operating lever applied to a conventional diaphragm type pump.

Fig. 2 is an enlarged sectional view of the lever and shoe illustrated in Fig. 1.

5 Fig. 3 is a transverse section through Fig. 2 along the line 3—3.

Fig. 4 shows a modified form of slidably mounted shoe construction.

10 Fig. 5 is a transverse section along the line 5—5 of Fig. 4.

Fig. 6 shows another modification of slidably mounted shoe.

Fig. 7 is a transverse section along the line 7—7 of Fig. 6.

15 Referring now to Figs. 1, 2 and 3, the numeral 11 refers to an eccentric. A conventional diaphragm type pump 15 formed with a mounting bracket 16 includes a diaphragm (not shown) and operating stem 19, secured at its lower end to the diaphragm.

20 Pump operating lever 22 is a curved, channel-shaped sheet metal member formed with a central opening 23 through which passes journal shaft 24. One end of lever 22 is bifurcated as at 25 to receive operating stem 19. Stem 19 is formed with a head 26, against which is seated metal washer 27, resilient washer 28, and hard plastic washer 29. A coil spring 30 normally biases the diaphragm and its stem 19 downwardly, thus urging washer 29 into contact with the upper surface of the bifurcated portion 25 of lever 22.

25 A contact shoe 31 formed with a concave arcuate upper face 31a for engagement with eccentric 11, and a plane lower face 32 for engagement 30 with the web portion of lever 22, is slidably secured to lever 22 by a pin 33 which is mounted for slidable movement in longitudinal slot 34 in the end portion of the web of lever 22. The contact shoe 31 extends laterally at each side of 35 the longitudinal side edges of the channel-shaped operating lever 22 and is provided with depending side flanges which embrace the side edges of the lever 22 to retain the shoe against lateral displacement. The depending side walls of the shoe 31 are so positioned with respect to the side walls of the lever as to provide suitable clearance to prevent binding during the sliding movement of the shoe on the bearing face of the lever. The bearing face of the lever is illustrated as a flat surface at the end portion of the lever structure.

35 The concave arcuate face 31a of shoe 31 is of the same radius as eccentric 11 and is urged into contact with the surface of eccentric 11 by coil spring 35, one end of which is seated in a recess 40 55 36 in pump bracket 16, the other end being seated

against the lower surface of the web of lever 22, about upturned locating member 37.

During operation of the engine, as eccentric 11 rotates, shoe 31 remains at all times in contact with the eccentric and slides back and forth on lever 22 to accommodate itself to the movement of the eccentric. As has been indicated above, the arrangement provides large, long-wearing bearing surface both between the shoe and the eccentric and between the shoe and the lever.

A modified form of slidably mounted shoe is illustrated in Figs. 4 and 5. The shoe 48 is stamped out of sheet metal and has a concave arcuate upper face 41 for engagement with the cam surface. At either end of the arcuate surface, extending end portions are bent under to form, with the bottom of the arcuate portion, a relatively large, flat bearing surface for slidable engagement with the lever web. Downwardly extending flanges 42 are formed on either side of the arcuate face, and tabs 43 extending inwardly from the lower edge of each of the flanges slidably secure the shoe to the lever. Tabs 43 ride in a shallow notch 44 in the flange lever 22, the ends of notch 44 serving as stops on longitudinal movement of the tabs and shoe.

Another form of slidably mounted shoe is shown in Figs. 6 and 7. In this modification the shoe 45 is generally similar to the shoe of Figs. 4 and 5, except for the shape of the web portion, the ends of which are not bent under the arcuate portion, but project outwardly.

Operation of the modified shoes 48 and 45 is the same as that of shoe 31 described above.

It will be understood that the forms described and illustrated herein are but the preferred embodiments of my invention, and that exclusive use is contemplated of all modifications coming within the scope of the appended claims as will occur to those skilled in the art.

I claim:

1. In a pump for operation by an engine rotated cam that is convex along its entire working surface, an operating lever mounted on a transverse pivot, a bearing surface formed at one end portion of said lever, a cam follower shoe having a bearing surface on one face in sliding contact with said bearing surface of said lever, said cam follower having a second bearing surface formed as a section of a cylinder and attached to said operating lever by a pin and slot connection positioned so as to permit sliding of the cam follower upon the lever in a plane parallel to the axis of said transverse pivot and to permit the full area of said second bearing surface of said follower shoe to remain in contact with the working surface of the rotatable cam while spreading said lever bearing surface along a substantial portion of said lever.

2. In an eccentric and follower mechanism, an eccentric having a surface that is convex along its entire working periphery and follower mechanism including a lever member and a shoe member, said shoe member being formed with a concave surface for receiving the convex surface of said eccentric, said lever being formed with a bearing surface at one end portion upon which said shoe member is supported for sliding movement so as to maintain said cam and shoe surfaces in full surface engagement during oscillation of said lever, the end portions of said shoe member projecting toward said lever bearing surface and being in sliding engagement therewith, and the longitudinal side faces of the shoe member being flanged downwardly to embrace the

side of the lever member, one of said members being provided with spaced walls defining stops, and the other member having a projecting portion positioned between said stops, whereby a sliding movement of the shoe member on the bearing face of the lever is limited in both directions.

3. In an eccentric and follower mechanism, an eccentric having a surface that is convex along its entire working surface and follower mechanism including a lever member and a shoe member, said lever member being formed with a bearing surface at one end portion upon which said shoe member is supported for sliding movement, said shoe member being formed with a concave face for receiving the convex surface of said eccentric in surface contact relationship, the end portions of the shoe member being flanged downwardly for sliding movement with the bearing face of the lever, and the longitudinal side faces of the shoe member being flanged downwardly to embrace the sides of the lever member, said lever member being formed with elongated recesses defined at their ends by wall portions, and the flanged portions of the side faces of said shoe member being provided with inwardly projecting tabs which travel between the walls of said recesses, thereby limiting the sliding movement of the shoe on the lever.

4. In a fuel pump of the type having a housing and a lever pivotally mounted thereon with a projecting end for actuation by an operating cam, which is convex along its entire working surface, a bearing surface on said end of said lever, and a cam follower shoe carried on said bearing surface and having a concave working face for continuous surface contact with the cam working surface, said shoe being slidably longitudinally of the lever along said bearing surface under the influence of the rotating cam associated therewith.

5. Eccentric and follower operating mechanism for a fuel pump comprising a cam which is convex along its entire working surface, a pivoted lever with a bearing surface at one end thereof, and a wear shoe with a concave working face having continuous surface contact with said cam working surface during operation, said shoe having an opposite surface mounted on said lever bearing surface for sliding movement longitudinally of the lever.

6. Eccentric and follower mechanism for a fuel pump comprising a cam which is convex along its entire working surface, a lever mounted on a transverse pivot and having a longitudinal bearing surface at one end thereof, and a bearing shoe carried by said bearing surface of said lever and having a concave working face in continuous surface contact with said cam working surface, said shoe being mounted to slide back and forth in a direction longitudinally of said lever bearing surface during operation.

7. Eccentric and follower operating mechanism for a fuel pump comprising a cam which is convex along its entire working periphery and which is rotatable on a fixed axis, a pivoted lever with a bearing surface at one end portion thereof, and a wear shoe with a cam engaging part in surface contact with said cam, portions of the shoe being located at each side of the cam axis, said shoe also having a surface slidably back and forth on said lever bearing surface in a direction of the length of the lever.
